US00D572195S

(12) United States Design Patent
Lin et al.

(10) Patent No.: US D572,195 S
(45) Date of Patent:  Jul. 1, 2008

(54) CLIPPING COVER

(75) Inventors: Kuo Chin Lin, Tu-Cheng (TW); Feng Zhu, Tu-Cheng (TW); Hua Lian Li, Tu-Cheng (TW)

(73) Assignee: Cheng Uei Precision Industry Co., Ltd., Taipei Hsien (TW)

() Term: 14 Years

(21) Appl. No.: 29/270,789

(22) Filed: Jan. 4, 2007

(51) LOC (8) Cl. 13-03

(52) U.S. Cl. D13/133; D13/154

(58) Field of Classification Search D13/133, D13/137.1, 138.1, 139.1, 146, 147, 154, 184, D13/199; 439/43, 95, 92, 93, 172, 252, 247, 439/248, 271, 272, 353, 357-358, 362, 372, 439/378, 527, 529, 538, 569, 680, 558, 606-610, 439/731

See application file for complete search history.
